UNITED STATES PATENT OFFICE.

THOMAS F. LOFTUS, OF WEST PHILADELPHIA, AND FRANK E. BRAZEAL, OF LANS-
DOWNE, PENNSYLVANIA.

AUTOMATIC SHUTTLE-STOP FOR LOOMS.

1,357,066.

Specification of Letters Patent. Patented Oct. 26, 1920.

Application filed October 29, 1919. Serial No. 334,200.

To all whom it may concern:

Be it known that we, THOMAS F. LOFTUS and FRANK E. BRAZEAL, citizens of the United States, and residents, respectively, 5 of West Philadelphia, in the county of Philadelphia and State of Pennsylvania, and Lansdowne, in the county of Delaware and State of Pennsylvania, have invented certain new and useful Improvements in 10 Automatic Shuttle-Stops for Looms, of which the following is a full, clear, and exact description.

This invention relates to factory looms and has particular reference to safety appliances for such machines.

The primary object is to prevent what is known as the "shuttle smash" or the breaking of the warp ends.

Another object of the invention is to prevent damage to the mechanism and injury to the weaver in the event that two shuttles are caused to collide as a result of the weaver making the mistake in putting shuttles in the shuttle race at both sides of the 25 loom.

Another object of the invention, in the carrying out of the primary object, is to cause the loom to stop whenever two shuttles are in position to be picked simultaneously from opposite sides.

Another object of the invention is to cause the loom to stop automatically in the event that one shuttle should stop half way in a shuttle box when the box is on the 35 descent, and another shuttle is about to be picked from the opposite side, thereby preventing the breakage of picker sticks, as well as other damage to the machine.

The colliding of shuttles in mills is an 40 every day occurrence, and among the causes of such conditions are the following: The weaver putting shuttles in the wrong shuttle box, broken picker straps, picker sticks, sweep sticks, heel spring, or box vibrators, 45 or any part of the box motion getting out of order such as vibrators binding in socket or comb, or getting out of time.

Our improvement, therefore, in short is 50 designed to stop the loom in the event of any of these unfavorable conditions so as to prevent the undesirable results that are likely to follow. With the stopping of the loom the weaver will of course correct the faulty condition and start the loom again 55 in the regular way, if the conditions are

right, but if he has failed to correct all of the faults it will be impossible for him to start the loom because of our safety appliance.

With the foregoing and other objects in view the invention consists in the arrangement and combination of parts hereinafter described and claimed, and while the invention is not restricted to the exact details of construction disclosed or suggested herein, 60 still for the purpose of illustrating a practical embodiment thereof reference is had to the accompanying drawings, in which like reference characters designate the same parts in the several views, and in which— 65

Figure 1 is a front elevation of a loom equipped with our improvement and in stopped position.

Fig. 2 is a left side elevation of the 70 same.

Fig. 3 is a vertical sectional detail on the line 3—3 of Fig. 4 showing the parts in working position.

Fig. 4 is a front elevation of the main parts of our improvement but with the 80 knock-off lever in section on the line 4—4 of Fig. 3.

Fig. 5 is a view corresponding substantially to Fig. 3, but indicating the automatic stopping position of the improvement.

Fig. 6 is a rear elevation of the bracket and latch portions of our improvement, the latch being in stopping position.

Referring now more specifically to the mechanism we show diagrammatically a 90 conventional loom comprising a breastbeam 10, a lay beam 11 adapted to oscillate toward and from the breastbeam and around the axis of a shaft 12. 13 indicates a rock shaft journaled in bearings 14 on the breastbeam and to either end of which is secured a starting and stopping lever 15 or 15' for the usual control of the operation of the loom. As indicated best in Fig. 2 the control is had through a clutch 16 fixed from 100 endwise movement upon a shaft 17 and toward and from which a driving pulley 18 is adapted to be moved by means of a lever 19 pivoted at 20. A link or bar 21 connects the lower end of the lever 15' to the 105 upper end of the lever 19 whereby to start the loom either hand lever will be drawn forward as indicated by the arrow *a* and to stop the loom either lever will be operated in the direction of the arrow *b*. The parts 110

thus far described in detail are or may be substantially the same as in ordinary use, and therefore this specification will not presume to describe at unnecessary length 5 either such parts or the normal ordinary working of the loom, all of which are well understood by those skilled in the weaver's art. We, therefore, shall confine ourselves essentially to the attachment constituting 10 our safety improvement.

22 indicates a bracket fixed to the front face of the lay beam 11. This bracket projects downward below the beam and is provided at its lower end with a vertical slot 23. 15 At the rear of the bracket is a pendulous latch 24 suspended from a horizontal pivot 25 journaled in the bracket and in a forward extension 22^a of the bracket. The lower end of the latch is adapted to oscillate between 20 stop lugs 26 on the rear face of the bracket so as to extend across and close the slot 23 or to lie at one side thereof as indicated in full and dotted lines respectively in Fig. 6. The normal tendency of the latch is to close the 25 slot which may be effected either by gravity or preferably by some auxiliary means such as a spring 26' acting thereon.

It being borne in mind that in looms of the character indicated there are two shuttle boxes represented diagrammatically at 27 30 and 28 and with which binders 29 and 30 co-operate respectively for holding the shuttles 31 in position to be picked by the picker sticks 32 and 33, we provide a pair of co- 35 axial rock shafts 34 and 35 journaled in the front of the lay beam 11 in bearings 36. Springs 37 or their equivalent act upon the rock shafts 34 and 35 and tend to rotate them in a clockwise direction in Figs. 3 and 40 5. To each of these rock shafts are secured two levers 38 and 39. The two levers 39 are located in close proximity to each other and adjacent to the abutting ends of the rock shafts and are so designed as to co-operate 45 in succession with a finger 40 fixed to the pivot 25 above described. When either shuttle 31 is in its box in position to be picked the binder 29 or 30 pertaining to the box in which the shuttle is located will be pressed 50 forward and in so doing it will swing the lever 38 forward thereby turning the rock shaft against the tension of the spring 37 acting thereon. This movement of the rock shaft in a counter clockwise direction as indicated in Fig. 3 causes the lever 39 fixed to the same rock shaft to swing downward and rearward away from the finger 40, the finger being normally held however in the 55 normal operation of the machine with the 60 shuttles working properly in alternation elevated by the other lever 39 so that under these conditions the latch 24 is always held at one side of the slot 23. The instant the shuttle leaves the shuttle box and binder the 65 spring 37 will act to move the lever 38 rear-

ward and the lever 39 forward and upward thereby insuring that the latch will not bridge the slot when the shuttle box is empty. If, however, any of the dangerous conditions 70 above enumerated should obtain such as the sticking of a shuttle in an intermediate position or the presence of two shuttles in the shuttle boxes at the same time both levers 38 will be pushed forward against the force of the springs 37 and both levers 39 will be 75 dropped downward and rearward. Consequently the latch 24 will be free to swing downward to the full line position of Fig. 6.

Secured to the rock shaft 13 is what we term a knock-off lever 41 the rear end of 80 which is provided with a cam face 41' and which in the normal operation of the loom is received in or through the slot 23 at each oscillation of the lay. When the starting shaft 13 is rotated by a forward pull on 85 either of the levers 15 or 15' to start the loom the knock-off lever 41 swings upward into the slot 23 or into a position to be received in the slot when the lay makes its next forward movement. It is essential, therefore, 90 that the latch 24 be located at one side of the slot 23 in order to start the machine. If the conditions are such that the latch 24 is in position to close the slot it follows that if the machine is at rest it can not be started 95 and furthermore if in operation the latch 24 will strike against the cam face 41' on the next forward oscillation of the lay and will cause automatically the movement of the starting levers in the direction of the arrow b and the throwing out of the clutch. The mechanism is of a relatively simple 100 mechanical nature being easily applied to any standard loom of the nature indicated herein and under normal operating conditions of the loom no obstruction nor inconvenience is occasioned by the attachment. With all the parts in proper running condition and position the machine is started, 105 manipulated or stopped in the usual manner. If, however, any of the dangerous conditions should result tending to cause damage 110 to the machine or injury to the operator the loom will be automatically and immediately stopped before such damage or injury can 115 result. No attention is required on the part of the weaver in the manipulation or control of the attachment. He simply performs his usual operations in the manipulation 120 or control of the loom and by the re-establishment by the weaver of the proper running conditions after a fault has occurred, the safety attachment will automatically be restored to the position that will provide for the proper normal operation of 125 the loom.

We claim:

1. The combination with a starting device for a loom, of a knock-off lever connected to the starting device, and means comprising 130

ing a pendulous latch coöperating automatically and directly with the knock-off lever to move the starting device to stopping position in the event of two shuttles occupying positions to be picked at the same time.

2. The combination with a loom lay having shuttle binders, of a starting and stopping device for the loom, a knock-off lever carried by the last mentioned device and having a cam-faced end projecting into co-operation with the lay, a pendulous latch, means acting upon the latch tending to hold it constantly in inactive position while the shuttle binders are operating properly in succession, and spring means to cause the latch to swing into operative position to co-operate with said cam-faced lever end in the event that the binders are not in proper working position and so cause the automatic 20 stopping of the loom.

3. The combination with a loom lay, a pair of rock shafts journaled thereon, means to oscillate the rock shafts in succession during the normal operation of the loom, a latch carried by the lay and depending from a horizontal pivot, means including a finger connected to said pivot and acting upon the latch to normally hold it inoperative during the normal operation of the loom, the 25 latch being movable to a different position automatically in the event of a dangerous condition of the loom, and a knock-off stopping member with which the latch coöperates in the latter position to automatically 30 stop the loom.

4. The combination with a loom lay and shuttle binders carried thereby, of a pair of coaxial rock shafts journaled upon the lay, a pair of arms connected to the remote ends 40 of the rock shafts and coöperating normally

in succession with the binders, a stopping device knock-off lever having a cam-faced free end, a movable member depending from a horizontal pivot carried by the lay and adapted in one position due to an abnormal condition of the loom to coöperate 45 with the knock-off lever to automatically stop the loom, and means acting between the rock shafts and said movable member to hold the latter in inactive position during the proper operation of the loom, said last mentioned means comprising a pair of levers fixed to the adjacent ends of the rock shafts, and a finger fixed to said pivot and normally held lifted by one or the other of 50 said adjacent levers.

5. The combination with a loom lay, a safety appliance comprising a bracket fixed to the lay and projecting downward therefrom, said bracket having at its lower end 55 a vertical slot and having a pair of stop lugs extending rearward on opposite sides of the slot, the bracket having also a forward bearing extension, a pivot journaled in the bracket and its extension, a pendulous 60 latch fixed to the rear end of the pivot and movable across the slot between said stop lugs, a finger connected to the pivot, means acting upon the pivot tending to throw the latch in position to close the slot, a pair of 65 rock shafts journaled on the lay, a pair of arms connected to the adjacent ends of the respective rock shafts and coöperating with said finger tending under normal operative conditions to hold the latch at one side of 70 the slot, and means to actuate the rock shafts, substantially as set forth.

THOMAS F. LOFTUS.
FRANK E. BRAZEAL.
